UNITED STATES PATENT OFFICE.

ALBERT A. MACLEOD, OF SWAMPSCOTT, AND LOUIS M. BROWN, OF BEVERLY, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY.

SHOE-MACHINE.

1,271,741.

Specification of Letters Patent.

Patented July 9, 1918.

Application filed December 12, 1914. Serial No. 876,949.

To all whom it may concern:

Be it known that we, ALBERT A. MACLEOD and LOUIS M. BROWN, citizens of the United States, residing at Swampscott and Beverly, respectively, in the county of Essex and State of Massachusetts, have invented certain Improvements in Shoe-Machines, of which the following description, in connection with the accompanying drawings, is a specification, like reference characters on the drawings indicating like parts in the several figures.

This invention relates to shoe machines and the embodiment of the invention selected for illustration is adapted to secure in place a strip of material upon the edge portion of a shoe bottom, for example about the heel seat of a welt shoe.

In the manufacture of a welt shoe the upper is lasted against the upstanding lip or rib of the innersole at the sides and toe of the shoe and secured temporarily in place by tacks. At the heel the upper is lasted down upon the heel seat and secured permanently by tacks. The upper is then sewed, together with the welt, to the lip or rib of the innersole from the breast edge of the heel seat around the periphery of the fore-part of the shoe and back to the breast edge of the heel seat. The upper, welt and innersole connecting seam is called the "inseam" and this sewing operation is performed by a special sewing machine called a "welter." In making some varieties of welt shoes the welt strip, instead of being severed at the heel breast line at the completion of the weltting operation, is allowed to extend from the inseam a sufficient amount so that it may be subsequently secured around the heel seat of the shoe, either to provide a continuation of the welt to which the outsole may be attached or to provide a rand between the heel seat and the lifts of the heel. Since the upper of the shoe has already been permanently secured to the heel seat by the lasting tacks, and innersoles are not usually provided with lips around the heel seat, the operation of attaching the extension of the welt to the heel seat cannot be performed by the welter. It is the general object of this invention to provide a machine which will be well adapted for performing the operation of at-

taching a welt to the heel seat of a lasted shoe.

The margin of the heel seat face of a lasted shoe presents an uneven surface because of the lasting tacks and folds of the upper. One important feature of this invention consists in means to facilitate the movement of the shoe progressively under the work rest of the welt attaching machine as the attaching operation proceeds. This means may comprise, as shown, a member which engages the heel seat over a considerable area adjacent to the line along which the welt is to be attached and which has a smooth surface in contact with which the surface of the heel seat may readily slide. In the illustrated embodiment of this invention this means comprises a plate which is adapted to be inserted between the welt and the heel seat and is located immediately in advance of the line of action of the welt attaching means, said plate being preferably connected movably to suitable supporting means. The plate may, as herein shown, have a normally depressed position to facilitate the insertion over it of the welt strip projecting rearwardly from the inseam, as above suggested, and the plate may be constructed and arranged to be moved upwardly to working position by the shoe as an incident to the operation of positioning the shoe in the proper relation to the welt attaching mechanism.

Another feature of the invention consists in a welt inclosing guide, of which the heel seat engaging plate, above mentioned, preferably forms a lower wall. As shown in the drawings, the welt attaching means is a tacker provided with a rigid work rest against which the shoe may be pressed upwardly to receive tacks. In the lower face of this rest is formed a recess across which the said engaging plate extends to confine the welt. An inclosing guide for the welt is important because resistance of the welt to being bent edgewise around the curved portion of the heel is likely to cause the welt to escape from the welt guide unless the welt is substantially surrounded. If the heel seat engaging plate forms the lower wall of the guide and has a normally depressed position the welt guide is normally open and the

welt is readily positioned in the guide by a movement of the shoe laterally of the welt strip; that is, by a substantially horizontal movement of the shoe into position beneath the tacker. This arrangement enables a welt strip having one end secured to the shoe to be introduced into the welt guide by the usual and necessary movements of the shoe into operative relation to the securing mechanism, and therefore without especial attention from the operator, and saves the loss of time which would be required to thread the welt end through a permanently closed guide.

These and other features of the invention will appear more fully from the following description when read in connection with the accompanying drawing and will be pointed out in the appended claims.

In the drawing,

Figure 1 is a perspective view of an embodiment of my invention;

Fig. 2 is a plan view of the welt guide and edge gage showing a shoe in position for the operation of attaching an extension of the welt about the heel seat thereof;

Fig. 3 is a side view of the parts shown in Fig. 2, including a sectional view of the top portion of the jack post; and

Fig. 4 illustrates the appearance of the shoe after the completion of the operation of securing the welt end about the heel seat.

Referring to Fig. 1 of the drawings, the reference character 2 indicates the frame of the machine. A driver 4 is mounted to be reciprocated at a slight inclination to the vertical and co-operates with a tack block 6 which reciprocates horizontally from a rearward position in which it receives tacks which are automatically fed to it from a raceway to a position under the driver which passes through the block and forces the tack into the work. A support 8 is secured to the machine frame 2, as shown in Fig. 3, and to the support 8 is adjustably fastened by screws and slots at 10 a rest or abutment 12 which is provided with a notch 14 over which the tack block 6 lies when in its forward position and through which the driver operates to insert a tack into the work. By loosening the screws 10, the rest 12 may be adjusted to bring the notch 14 into alignment with the driver. On the under face of the rest 12 and laterally in a line with the notch 14 is a recess or groove 16 which forms a guide for the welt which is to be secured to the work. At the back of the recess 16 is a member 18 which is arranged for adjustment to vary the size of the groove to adapt it to different widths of welting. The members 18 is T-shaped, as shown in Fig. 2, and is held in adjusted position by a screw and slot adjusting means 19. To the under face of the rest 12 is secured, as by rivets 20, a plate 22 to the forward end of which is mov-

ably secured, as by a hinge, at 24 a plate 26 which underlies the groove 16 and preferably conforms to the contour in plan of the forward portion of the rest 12. The right-hand or advance edge of the plate 26 may be upturned, as shown in Fig. 3, to facilitate the passage of the work thereunder.

An edge gage 30 is provided which preferably is a steeply inclined, frusto-conical fiber roll, the upper and larger periphery of which contacts with the side of the shoe at a point in very close proximity to the plane of the shoe bottom where the shape of the shoe is such that the edge gage will insure the securing of the welt at a uniform distance from the edge of the last bottom. A handle 32 is provided which may be grasped by the operator by the same hand which holds the shoe in position against the rest 30, and this handle may conveniently be formed as an extension of the pivot upon which the roll 30 is mounted.

The jack for supporting and positioning the shoe relatively to the welt guiding and attaching means is in most respects similar to that shown in United States Letters Patent No. 919,424, granted April 27, 1909, on application of William H. Cuff, and reference may be had to that patent for details of the mechanism not herein given.

The center about which the jack post swings in its to and fro movements to carry the shoe into and out of position to be operated upon should be in vertical alinement with the driver in order to firmly support the shoe and to effect this a toothed segment 42 which engages a rack 40 is formed on a yoke member 46 having rearwardly projecting arms to which are pivoted at 48 arms of a second yoke 50 on which the jack post 52 is mounted. The jack post, therefore, swings about the pivot 48 to carry the work to and from the operating parts of the machine and also rocks laterally upon the segment 42 so that the shoe may be moved in a substantially horizontal plane beneath the rest 12. The jack as a whole may be lowered to facilitate the introduction of the work beneath the rest 12 by means of a treadle 54 against the action of a spring 58, and the jack post may be quickly adjusted vertically to accommodate different heights of last and to quickly adjust the force with which the shoe will be upheld against the rest 12 by operating a handle 62 to vary the relation of the cam faces 64, 66. By means of the yokes 46, 50, it will be apparent that the pivot about which the jack post is swung is carried rearwardly to a point which is substantially in vertical alinement with the driver and with the heel pin upon which the shoe is spindled when the shoe is in position to be operated upon. The jack is prevented from swinging about the supporting post 70 by a block 72 mounted on one of the sup-

porting brackets of the jack and engaging a groove 74 formed in the jack frame as shown in Fig. 1.

To prevent the catching of the upper between the crown of the last and the flange at the base of the heel pin, the construction shown in Figs. 1 and 3 is provided which comprises a collar 80 which slips easily upon the last pin 82 and in the periphery of which are pivoted a series of toggles or jointed members 84, the opposite ends of which are similarly pivoted in a flange formed on the mid portion of the pin 82 which is seated in the usual manner in the top of the jack post. The toggles are normally held in a partially straightened position, as shown in Fig. 1, by means of a spring 86 acting on a pin 88 which passes through the collar 80 and rides in a vertical slot 90 in the last pin 82. The hole in which the spring 86 is seated is extended upwardly as far as the slot 90 to permit the spring to act upon the pin 88 and to hold the toggle members in the position shown in Fig. 1. When the shoe is presented to the last pin 82, the action of the toggle members as they are bent by pressure of the crown of the last upon the collar 80 is to push the upper away from the last and heel pin so that it cannot be pinched between the crown of the last and the collar 80 and injured when the last is forcibly upheld against the rest by the jack.

The mechanism described in the above paragraph is not claimed herein but is made the subject-matter of a divisional application Serial No. 231,514, filed April 29, 1918.

Having fully described our invention, what we claim as new and desire to secure by Letters Patent of the United States is:—

1. A machine of the class described having, in combination, welt attaching mechanism for securing a welt progressively to a shoe bottom, a rest to which the work is held to bring it into operative relation to the attaching mechanism, and a plate arranged adjacent to the rest and constructed to facilitate movement of the shoe relatively to the rest as the attaching operation proceeds.

2. A machine of the class described having, in combination, welt attaching mechanism for securing a welt progressively to a shoe bottom, a rest for locating the work in the proper vertical position relatively to the attaching mechanism, and a plate having a relatively large area of contact with the shoe arranged to contact with the shoe bottom in advance of the attaching mechanism and constructed to facilitate movement of the shoe relatively to the rest.

3. A machine of the class described having, in combination, welt attaching mechanism, a rest for locating the work relatively to said attaching mechanism, and a plate constructed and arranged to be in-

troduced between the welt and the shoe bottom to facilitate movement of the shoe relatively to the rest.

4. A machine of the class described having, in combination, mechanism for attaching a welt to the peripheral portion of a shoe bottom, a work rest for locating the work relatively to the attaching mechanism, said rest having a recess therein for the reception of the welt, and a movable plate having a normally depressed position relatively to said rest and constructed and arranged to be moved upwardly to working position as an incident to the operation of positioning the shoe in the proper relation to the welt attaching mechanism.

5. A machine of the class described having, in combination, welt attaching mechanism, a rest having a recess in its lower face adapted to hold a welt to guide it into position to be secured progressively to a shoe bottom and a work engaging plate movably mounted upon the under side of the rest to permit introduction of the welt into the recess of the rest by a lateral movement of the welt, and constructed and arranged to be held by pressure of the work across the said recess to close the recess and form a welt inclosing guide.

6. A machine of the class described having, in combination, welt tacking mechanism, a rigid work rest against which the shoe may be pressed upwardly to receive tacks and having in its lower face a recess for the reception of the welt, and a plate movably mounted below said recess and having a normally depressed position to permit the introduction of the welt over the plate into the recess by a substantially horizontal movement of the shoe laterally of the welt strip, said plate being constructed and arranged to be lifted by the presentation of the work against the rest to form a lower wall for the recess and to maintain the welt in proper position to be tacked progressively to the shoe bottom.

7. A machine of the class described having, in combination, welt attaching mechanism, means for supporting the work against the action of the attaching mechanism, said means being movable to and fro to bring the work into and out of operative position, a work rest having a recess for receiving the welt, and a plate mounted upon the under side of the rest and having a normally depressed position to permit the entrance of the welt into the recess by the to and fro movements of the work and constructed and arranged to be held by pressure of the shoe against the under side of the rest to close the recess and form a guide which surrounds the welt.

8. A machine of the class described having, in combination, welt attaching mechanism, work supporting means mounted for

to and fro movement about a center located beneath the driver of the attaching mechanism, a rest having a recess for guiding the welt in position to be secured to the shoe bottom, said recess being located between the driver and the pivot of the work support, and a plate pivoted upon the under side of the guide constructed and arranged to be held in closed position by the work support, and to drop down to permit introduction of the welt into the recess by movement of the work support about said center into operative relation to the tacking means.

In testimony whereof we have signed our names to this specification in the presence 15 of two subscribing witnesses.
